UNITED STATES PATENT OFFICE

ROBERT GOLDSCHMIDT, OF BERLIN-KARLSHORST, GERMANY, ASSIGNOR TO GENERAL ELECTRIC COMPANY, A CORPORATION OF NEW YORK

OSCILLATION GENERATOR

Application filed June 20, 1928, Serial No. 286,946, and in Germany July 7, 1927.

My invention relates to electron discharge oscillation generators and more particularly to the winding systems thereof. It has for its purpose to provide an oscillation generator which is particularly adapted for use in connection with delicate measuring devices, bridges and the like.

More particularly my invention has for its purpose to provide an electron discharge oscillation generator in which the potential or field distribution in the load winding is symmetrical with reference to the center of the winding system.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawings, in which Fig. 1 represents a conventional circuit of an oscillation generator of the type to which my invention relates, and in which Figs. 2 to 7 inclusive illustrate the construction and arrangement of the windings thereof.

Referring to Fig. 1 of the drawings, 1 represents an electron discharge device having the usual cathode, anode and grid together with a grid winding 2, which is connected between the grid and cathode, and anode winding 3 which is connected between the anode and the cathode, and an output, or load winding 4, all of which windings are inductively related. 5 represents a condenser which is connected in shunt with the winding 3 and which together therewith comprises the oscillatory circuit of the generator.

The windings 2, 3 and 4 may be assembled in the manner shown in Fig. 2. It will be seen that each of the windings are of the cylindrical type and that they are arranged in parallel spaced relation, and further that the load winding is divided into sections which are disposed upon opposite sides of the grid and anode windings, and that they are arranged symmetrically with reference thereto, the inner terminals of the different

sections of the winding 4 being connected by means of a conductor 6.

While advantages result from the use of windings arranged in accordance with Fig. 2 it is preferable that the windings be assembled in the manner shown in Fig. 3. In this figure it will be seen that not only is the load winding divided into sections but also the grid and anode windings are likewise divided into sections, each of these sections comprising coils of the cylindrical type, the sections of each winding being symmetrically disposed upon opposite sides of a plane 7 extending parallel with the coils and which may be designated as the center of the windings. The inner terminals of each of the anode, grid and load windings are connected together by conductors 8, 9 and 10 respectively. If desired, however, either of the grid or anode windings may comprise a single coil, the other windings being disposed symmetrically with reference thereto. The operation of the system shown in Fig. 3 is improved if the symmetry of the arrangement is increased by winding the coils of each winding in opposite sense with reference to each other in the manner shown in Fig. 6. The effect of stray fields is reduced by this arrangement.

In Figs. 4 and 5 of the drawings respectively I have shown a side elevation and perspective view of the winding assembly. It will be seen that each of the sections of the different windings is provided with an individual base 11, which is adapted for slidable engagement with a recessed portion of a common support 12. This arrangement provides a convenient means whereby the space relation of the coils may be adjusted in order to compensate for minor unevenness in the symmetry which may occur resulting from the assembly as shown in Fig. 3, thereby producing a more symmetrical field and potential distribution in the load coil.

The arrangement of the windings within the coils and particularly that of the load coil is shown in Fig. 6. In order to prevent outside disturbances from affecting the field or potential distribution in the load winding,

each of the sections of the load winding is preferably shielded by means of a metallic protecting mantle 13 which is wound about the cylindrical coil in the manner shown in Fig. 7. This protecting mantle consists preferably of a thin copper band of five or ten millimeters breadth, which is wound about the winding in a manner such that successive turns overlap at the edges thereof. Since this protecting mantle extends about the winding in the direction of the magnetic field it is cut only by a few lines of force and hence substantially no eddy currents are produced therein. Conductors which extend from the load winding to the bridge, or other measuring instrument, may likewise be shielded to preserve the symmetrical potential distribution which has been established.

Heretofore in the operation of measuring apparatus, bridges and the like the necessary alternating current has been produced by generators, or transmitters, which are located in proximity to the bridge and which usually have windings arranged upon laminated iron cores. It has been found, however, that with such an arrangement satisfactory operation of the bridge is difficult to attain due particularly to the property of the iron in distorting the wave form when in the neighborhood of saturation. Further since the transmitter is arranged in proximity to the bridge it may cause disturbances resulting from its stray fields, which stray fields also amount to an element of loss. These disadvantages may be substantially overcome by use of a generator having windings constructed as described.

While I have shown particular embodiments of my invention it will be understood that I do not wish to be limited thereto since modifications may be made without departing from the spirit and scope of my invention as set forth in the appended claims.

What I claim as new and desire to secure by Letters Patent of the United States is:

1. An oscillation generator comprising an electron discharge device having a grid and anode, and a plurality of inductively related windings including a winding connected to the grid, a winding connected to the anode, and a load winding, said load winding being divided into sections which are equally disposed on opposite sides of said windings connected to the grid and anode whereby a substantially symmetrical field distribution in said load winding is produced.

2. An oscillation generator comprising an electron discharge device having an anode and a grid, and a plurality of inductively related windings including a winding connected to the grid, a winding connected to the anode, and a load winding, each of said windings being divided into equal sections and

the sections of each winding being connected and arranged symmetrically with reference to a common center whereby a symmetrical potential distribution in the load winding is produced. 70

3. In combination, an oscillation generator comprising an electron discharge device having an anode and a grid, and a plurality of inductively related windings including a winding connected to the grid, a winding connected to the anode, and a load winding, each of said windings comprising a plurality of coils arranged in parallel spaced relation, the coils of each winding being symmetrically disposed with reference to a common plane and means for relatively adjusting the said coils in space to produce a symmetrical field distribution in the load coil. 75 80

4. In combination, an oscillation generator comprising an electron discharge device having an anode and a grid, and a plurality of inductively related windings including a winding connected to the grid, a winding connected to the anode, and a load winding, each of said windings comprising a plurality of coils arranged in parallel space relation, the coils of each winding being symmetrically disposed with reference to a common plane, a common support for said coils, each of said coils being provided with a base adapted for slidably engagement with said support whereby said coils may be relatively adjusted in space to produce a symmetrical field distribution in said load coil. 85 90 95

5. An oscillation generator comprising an electron discharge device having a grid and anode, and a plurality of inductively related windings including a winding connected to the grid, a winding connected to the anode, and a load winding, said load winding being divided into sections which are equally disposed on opposite sides of said windings connected to the grid and anode, the sections of the load winding on opposite sides of the grid and anode windings being oppositely wound with reference to each other. 100 105 110

6. An oscillation generator comprising an electron discharge device having a grid and anode, and a plurality of inductively related windings including a winding connected to the grid, a winding connected to the anode, and a load winding, said load winding being divided into sections which are equally disposed on opposite sides of said grid and anode windings whereby a substantially symmetrical field distribution in said load winding is produced, each of the sections of the load winding having a conducting metallic covering wound about it in the direction of the flux. 115 120 125

In witness whereof I have hereunto set my hand this 23rd day of May, 1928.

ROBERT GOLDSCHMIDT.
